HOSIERY AND THE METHOD OF MAKING IT

Erwin Ruckel, Richmond Hill, N. Y.

Application August 13, 1938, Serial No. 224,668

5 Claims. (Cl. 66—185)

This invention relates to a new and useful improvement in hosiery and method of knitting the same and in particular to the construction of the heel tabs.

5 A comparatively recent development in the hosiery industry is the utilization of a standard full fashioned flat legger for knitting the leg and foot of a stocking as a unit, thus making a legger the substantial equivalent of a single unit machine, with the exception that the heel tabs are knit subsequently as a separate operation.

When a legger is used in this way the last course of the high heels is utilized as the anchorage for the first course of the sole portions lying on each side of the instep. However, since the first course of each sole portion must ultimately be joined to the side of the corresponding heel tab, the sole portions must be severed from the high heels, which involves the destruction of 10 those portions of the first two or three courses directly below the ends of the high heels, with the exception of a few loops at the inner corners, which are retained to strengthen the fabric at the junction between the high heels, heel tabs, 15 sole portions and instep. Therefore, it is customary to consider these as severing courses between the ends of the high heels and the beginning of the sole portions.

Because of the elimination from the finished 20 stocking of these severing courses and the inclusion of the remaining portions of the same courses in the instep, it is inevitable that a pucker will occur at the inner corners just mentioned which impairs the appearance of the stocking 25 in a conspicuous place and imposes excessive strain upon the loops of the sole portions and heel tabs at this point.

One of the objects of this invention is to replace the partial courses lost by severing with other 30 courses so that the pucker referred to will be eliminated and also to supply in certain constructions which will be hereinafter described, a course or courses which will insure neat and durable joining of the heel tabs and sole portions.

45 To illustrate the invention the fabrics shown in the drawings have been chosen:

Figure 1 illustrates part of the leg and the foot of a stocking blank knit as a unit upon the standard legger;

50 Figure 2 is a view illustrating the same stocking blank after it has been transferred to the heeling machine and the first course of the heel tabs knit;

55 Figure 3 is a view of the stocking blank after the heel tab has been partly knit and joined to the corresponding sole portion to the same extent;

60 Figure 4 is a view of the stocking blank illustrating further progress in the knitting of the

heel tab and the joining of it to the corresponding sole portion;

Figure 5 is a similar view after the heel tab is completed and joined to the sole; and

Figure 6 is a view of the completed foot and the 5 adjacent part of the leg.

As stated, Figure 1 shows the leg 1 and foot 2 of a stocking assumed to have been knit as a unit upon a legger. The sole portions 3 are joined to the high heels 4 by severing courses 5. (The 10 fact that in a well proportioned stocking the foot where it joins the leg is wider than the leg and the methods by which this extra width may be obtained have been ignored, since it forms no part of this invention, although the invention is 15 applicable to stockings of that character.) As already generally explained, these severing courses 5 are in reality the outer portions of full courses which extend all the way across the stocking blank and elsewhere (i. e., inside of the points 20 6) form a permanent part of the fabric.

Before the high heel and sole portions are severed the last course of the high heels and the first real course of the sole portions are topped onto a double topping stand. Then the high heels 25 may be separated from the sole portions by cutting the fabric along severing courses 5.

Then the last course of the high heels 4 and the first course of the sole portions 5 may be swung into alignment and placed upon the needles of a suitable machine for producing the heel tabs as shown in Figure 2.

Heretofore, the heel tabs have been knit to the ends of the high heels 4 only and the sides later joined directly to the ends of the soles, either 35 progressively with the knitting of the heel tabs, or by a subsequent operation, with the consequent production of the undesirable puckers recently mentioned adjacent the inner ends 6 of the severing courses 5. By this invention, as shown 40 in Figure 2, the first course 8 of each heel tab 9 is not confined to the heel tab, as is the usual practice, but extends completely across not only the end of the high heel, but also across the first course of the corresponding sole portion 3. This 45 extended course may be followed by other courses of similar extent to a number presumably, but not necessarily equal to the severing courses lost in severing the sole portions from the high heels 4. The last of these heel tab extension courses 8 may 50 then be joined to the side of the heel tab 9 by any of the methods usually employed in joining the end of the sole to the side of the heel tabs, with the result that the undesirable puckers are eliminated.

55 This invention is particularly useful in knitting hosiery of the construction disclosed by my co-pending application, Serial No. 206,512, filed May 7, 1938, in which the difficult operation of double topping the last course of the high heels

and the first course of the sole is greatly simplified by utilizing the corresponding parts of the course or courses following the severing courses 5 to form a run-stop structure, as shown at 11, to prevent the loops of the succeeding courses from running. This permits the course following the run-stop course and which constitutes the first real course of the sole to be topped in a hit and miss manner without regard to whether every 10 sinker loop is topped upon a topping point. Since, in this fabric the severing courses 11 required for run-proofing, although they remain, are, nevertheless, excluded from the flat fabric proper, the discrepancy between the number of 15 courses in the high heel 4 and sole portions 3, as compared with the instep portions, is increased and the pucker adjacent the inner end of the severing courses correspondingly aggravated.

By this invention this defect can be eliminated 20 by extending across the sole a sufficient number of the initial courses of the heel tabs as described above, to compensate not only for the last severing course, but also for the courses forming the run-stop 11, the last extension course being, 25 as before, the course by which the sole portion is joined to the side of the corresponding heel tab. This is also shown in Figure 2, which, as stated, illustrates the fabric after the soles 3 and high heels 4 have been severed, the last course of the high heels and the first real course of the sole portions topped and swung into alignment and placed upon the needles of the machine which knits the heel tabs. The first course 8 of the heel tabs is knit across not only the heel tab proper, but, as described above, is extended across the first sole course. This course may be followed by additional courses of similar extent, if desired, to compensate for the courses destroyed by severing and for the run-stop, the last 40 heel tab extension course 8 of this character being the course which is joined to the side of the heel tabs.

As already generally stated, the sole portion and heel tabs may be joined after the heel tabs 45 have been completed, or they may be joined progressively with the knitting of the heel tabs. When the latter method is employed, the first course of the heel tabs is knit and then the loops of the first course of the sole portions are transferred outward by one needle so that the loop 50 adjacent the inner edge of each heel tab will be superposed upon the innermost loop of the heel tab course, and will be incorporated in the fabric in that position by the knitting of the next course of the heel tab.

When the second course of the heel tabs is knit, the remaining loops of the first course of the sole portions are again transferred outward by one 55 needle for the same purpose, and with the same result, and so on, until the heel tabs are completed, which also completes the joining of them with the sole portions.

Since there are many courses in the heel tabs and the first course of loops of the sole portions 60 has to be transferred as described after the knitting of each heel tab course, a great deal of wear and strain is imposed upon these sole portion loops, so that it is inevitable that they become seriously weakened. By the present invention this difficulty is eliminated. As already explained, the heel tab extension course 8 in Figure 65 2 is the course by which the sole portions are joined to the side of the heel tabs, and, conse-

quently, would be subject to the wear and tear of progressive joining. However, as illustrated by Figure 3, after a certain number of heel tab courses 9 have been knit, and an equivalent number of loops 8a of the extension course 8 5 joined thereto, another heel tab extension course 12 may be knit across the heel tab proper 9 and also across the remaining loops of the extension course 8. This new heel tab extension course, which is composed of fresh unworn loops, then 10 becomes the course to be joined progressively to the side of the heel tab as the heel tab courses are knit. After, say, one half of the heel tab courses are knit and joined to the corresponding sole courses, as shown at 12a in Figure 4, another 15 heel tab extension course 13 may be knit across the heel tab and also across the remaining loops 12b of extension course 12. This heel tab extension course 13 takes the place of course 12 as the course which is joined to the remaining 20 courses of the heel tabs as they are knit to complete the heel tab and its joining to its sole portion, as shown in Figure 5. Any desired number of such heel tab extension courses may be employed to supply a fresh and unimpaired anchorage for the corresponding courses of the heel tabs. In this way a very serious defect, which has hitherto been considered unavoidable in the progressive method of joining the sole portions and heel tabs, is effectively eliminated without 30 appreciably complicating the knitting process.

I claim:

1. A stocking which includes heel tabs and corresponding sole portions and means by which each heel tab is joined to the corresponding sole portion, consisting of a plurality of spaced courses of loops each extending across said heel tab and also from the inner edge of said heel tab to the outer edge of said sole portion.

2. The method of knitting a stocking which 40 consists of knitting the leg and foot portions as a unit, subsequently knitting a heel tab to the end of each high heel, the first course of each heel tab being extended to the outer edge of the corresponding sole portion and subsequently 45 joining said sole portion to said heel tab by means of said extended course.

3. The method of knitting a stocking which consists of knitting the leg and foot portions as a unit, subsequently knitting a heel tab to the end of each high heel, extending a plurality of heel tab courses from the inner edge of the heel tab to the outer edge of the corresponding sole portion and joining said heel tab and sole portion by means of said extended courses.

4. The method of knitting a stocking which consists of knitting the leg and foot portions as a unit, subsequently knitting a heel tab to the end of each high heel, extending a plurality of spaced heel tab courses to the outer edge of the corresponding sole portion and joining the sole portion to the heel tab by means of said extended courses progressively course by course with the knitting of the heel tab.

5. The method of knitting the leg and foot 65 portions as a unit, subsequently knitting a heel tab to the end of each high heel, at least the first course of each heel tab being extended to the outer edge of the corresponding sole portion and subsequently joining said sole portion to said heel tab by means of the last of said extended 70 courses.

ERWIN RUCKEL.
